UNITED STATES PATENT OFFICE.

WILLIAM B. WEESE, OF GRANT CITY, MISSOURI, AND LEWIS M. CRAWFORD, OF VALLEY JUNCTION, IOWA.

BINDER AND MOWER TRUCK.

1,163,608.

Specification of Letters Patent.

Patented Dec. 7, 1915.

Application filed February 16, 1915. Serial No. 8,642.

To all whom it may concern:

Be it known that we, WILLIAM B. WEESE and LEWIS M. CRAWFORD, citizens of the United States, and residents of Grant City and Valley Junction, in the counties of Worth and Polk and States of Missouri and Iowa, respectively, have invented a certain new and useful Binder and Mower Truck, of which the following is a specification.

10 The object of our invention is to provide a tongue truck of simple, durable, and inexpensive construction, peculiarly adapted for use with harvesting machines, such as mowers and binders.

15 A further object is to provide such a device, having a casting or supporting member of new and novel construction, peculiarly adapted for securing together two tongue members, and adapted also to serve as a portion of a bearing for the arm of a caster wheel.

20 Still a further object is to provide such a truck, so constructed and arranged that the horses may be hitched comparatively close to the machine.

25 Still a further object is to provide such a truck adapted to so assist in supporting the weight of the machine and to so connect the tongue members, as to permit the tongue to swing vertically but not horizontally.

30 Still a further object is to provide such a tongue truck as to assist in holding the machine against variations from a direct path of travel.

35 Our invention consists in the construction, arrangement and combination of the various parts of the device whereby the objects contemplated are attained, as more fully set forth, pointed out in our claim, and illustrated in the accompanying drawings, in which:

40 Figure 1 shows a side elevation partly in section of a tongue truck embodying our invention. Fig. 2 shows a top or plan view of the same, and Fig. 3 shows a vertical sectional view taken on the line 3-3 of Fig. 2.

45 In the exemplification of our invention illustrated in the accompanying drawings, we have used the reference numeral 10, to indicate generally the short permanent frame or tongue member secured to the mower, binder, or other machine, with which our improved tongue truck is to be used. The movable tongue 11 is to be secured to the member 10, in a suitable way,

to accomplish the purposes hereinbefore set forth. For making such a suitable connection, we have provided a connecting bracket on said member, comprising the vertical spaced parallel plates 12, adapted to receive between them the front end of the tongue member 10, and to engage the sides of said tongue member, and to be secured thereto by means of bolts 13 and nuts 14. The members 12 may be inclined slightly upwardly from their rear ends, as shown in Fig. 1. Formed on the forward ends of the members 12, are forward extensions 15. Secured to the side of the rear end of the tongue member 11, are plates 16, which are secured to said tongue, and to each other by means of bolts 17. The rear ends of the plates 16 extend beyond the tongue 11 and are received between the forward ends of the extensions 15, and are pivotally secured thereto by a bolt 18 and a nut 19. Mounted on the bolt 18 between the members 16 is a spacing sleeve 20. Formed between the members 15 in front of the tongue 10 is a transverse comparatively thick connecting member 21, preferably made integral with the connecting device, hereinbefore described, and having at its bottom a broad circular base 22. The base 22 comprises or forms a bearing member having at its periphery a downwardly extending flange 23, inside of which is an annular angular slot 24. Below the slot 24 and between the slot 24 and the middle of the base 22, are downward extensions 25 and 26, forming shoulders of the bearings. Below the bearing, formed on the base 22, is a coating bearing 27, having in its central upper surface an opening or recess 28, which receives the extension 26. Above the opening or recess 27 is a large opening or recess 29 to receive the extension 25. At its upper end the bearing 27 is formed with a peripheral upwardly extending annular flange 30, which is received in the slot or groove 24. The bearing 27 and body 21 and base 22 are provided with vertical openings which register with each other. Mounted on said openings is a large bolt 32, the head 33^a of which is countersunk in the lower part of the bearing 27. The upper end of the bolt 32 is screw threaded to receive a nut 33. Extending downwardly and curved rearwardly from the sides of the bearing 27, are arms 34, the lower ends of which are slightly enlarged 105 110

A TRACTOR TRAILER

and are provided with openings which register with each other and form bearings for an axle 35, on which is mounted a wheel comprising a hub 36, inside of which, surrounding the axle, is a sleeve 37, which may be removed and replaced when worn. Outside the hub 36 is an annular outwardly extending web 38, at the periphery of which is formed a broad rim 39, in the center of which is a sharp annular outwardly extending blade 40.

In the practical use, our improved truck may be used for mowers, binders, or other machines.

15 Our truck has a number of important advantages and accomplishes a number of important purposes. It will be noted that the arms 34 are comparatively short, and are made on a quarter circle, so that the wheel 20 is a caster wheel, and is comparatively small so as to be located close to the tongue 11. The bearing is strong and dust proof.

Our entire truck is comparatively small and makes it possible to hitch the team three 25 feet closer to the mower or binder than can be done with any other truck, with which we are familiar, and it is well known that a team can handle a load better when hitched close to it, and that less draft power is required. Another reason why the team can be hitched close to the machine arises from the 30 fact that the tongue can swing vertically but not laterally. This gives the team direct control of the machine in turning, so that with 35 a truck of this type the team could not turn into the sickle, which would be the case with all other trucks now in use. The advantage in draft of hitching close to the machine is well known. Such a close hitch, not only 40 gives the team a direct control of the machine, as hereinbefore suggested, but also gives the driver a better control of the team. The feature of a direct control of the machine is important both in field work, and 45 in hauling the binder, for instance, on an additional truck on the road; and is very important in making square turns in the field. A truck of this type assists in carrying the weight of the binder or mower, and 50 therefore releases the horses' necks from the strain of the direct downward draft, which the horses must ordinarily undergo in supporting the forward end of the tongue. The construction here shown is important for 55 the reason that the sickle may be swung to very low position for picking up down grass or grain.

On account of the fact that the truck takes considerable weight, it is possible to use a 60 binder or mower equipped with our truck

on softer ground, than is the case where no such truck is used. With a truck of this type, insomuch, as the tongue cannot turn laterally, the machine can be backed up or can be held back on a hill, which could not 65 be done with many of the trucks now in use.

The combination in which our truck is used, which includes the connecting device whereby the tongue is permitted to swing vertically but not laterally, in connection 70 with the comparatively low broad wheel with the central blade 40, assists in holding the machine in a straight line of travel. This combination is important on a side hill, where it is possible to hold the machine in 75 position for cutting a full swath of grain, without permitting the machine to slide or swing down the hill. This combination also largely obviates the side jerk of the tongue on the team, and prevents side draft. 80

The parts of our truck are so constructed and arranged that the truck may be readily and easily mounted on any tongue and machine.

It will be understood that some changes 85 may be made in the construction and arrangement of the details of our improved binder and mower truck without departing from the essential features and purposes thereof, and it is our intent to cover by this 90 application any such changes which may be included within the scope of our claim.

We claim as our invention:

In a tongue truck, a fixed tongue member, a movable tongue member, means for connecting said tongue members and for supporting a caster wheel comprising a member having spaced extensions receiving the end of the fixed tongue member, spaced forwardly extending members, a member connecting said extensions and adapted to abut against the fixed tongue member, having downwardly extending bearing shoulders and a downwardly opening annular groove, parallel members secured to said movable 100 tongue member and pivoted to said forwardly extending members, a bearing member having sockets receiving said bearing shoulders and an upwardly extending annular portion received in said groove, a bolt extended through said bearing member and said member connecting said first extensions. 110
